[57] CLAIM

The ornamental design for a combined stationery sheet and envelope, as shown and described.

DESCRIPTION

FIG. 1 is a top plan view of a combined stationery sheet and envelope showing my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a bottom plan view thereof;

FIG. 7 is a perspective view thereof, shown partially folded;

FIG. 8 is a perspective view thereof, folded for mailing and showing the address side; and

FIG. 9 is a perspective view thereof, folded for mailing and showing the side opposite FIG. 8.
